UNITED STATES PATENT OFFICE

171,021

TABLE LAMP

Anna Arch, New York, N. Y.

Application June 16, 1953, Serial No. 25,512

Term of patent 14 years

(Cl. D48—20)

To all whom it may concern:

Be it known that I, Anna Arch, a citizen of the United States, residing at New York city, State of New York, have invented a new, original, and ornamental Design for a Table Lamp, of which the following is a specification, reference being had to the accompanying drawing, forming a part hereof.

I claim:

The ornamental design for a table lamp, as shown.

ANNA ARCH.
